UNITED STATES PATENT OFFICE.

A. IRVING GRIGGS, OF WESTFORD, NEW YORK.

STOVE-BOARD.

SPECIFICATION forming part of Letters Patent No. 359,353, dated March 15, 1887.

Application filed November 14, 1885. Serial No. 182,802. (No model.)

To all whom it may concern:

Be it known that I, A. IRVING GRIGGS, a citizen of the United States, and a resident of Westford, in the county of Otsego and State 5 of New York, have invented certain Improvements in Stove-Boards and their Manufacture, of which the following is a specification.

My invention relates to the manufacture of stove-boards from sheet metal; and the invention consists partly in the process of manufacture and partly in the product or stove-board as an improved article of manufacture.

The object of my invention is to produce a stiff, durable, cheap, and handsome stove-board 15 made from a single sheet of cheap material—namely, tin-plate embossed throughout its entire extent; but this embossed tin-plate being a very refractory material, the usual means for beading the edge of the board cannot be employed, and, moreover, it is desirable to have the embossing on the plate extend over and ornament the bead also, and this embossing would be obliterated or marred by the spinning up of the bead, even if this process were 25 practicable.

Heretofore stove-boards have been made of sheets of brass and zinc, which are ductile metals and easily spun; but brass is a costly material and zinc is lacking in stiffness and durability. Such boards have also been made from 30 a sheet of tin cut to the proper shape, and a marginal strip of a ductile metal seamed to the edge of the tin-plate to form the ornamental bead. What is known as "crystallized" tin-plate, not embossed, has also been employed 35 for making a stove-board, the edge of the plain plate being crimped down over the edge of a wooden backing.

I mention the above constructions in order 40 to illustrate the state of the art up to the present time.

My invention in its entirety consists in first embossing the entire surface of a sheet of tin-plate large enough to form the board; then cutting this embossed sheet to the proper form 45 for the board; then passing the margin of the plate through a series of beading-rolls, whereby the "raw" edge of the metal is turned under or "hemmed" down and a raised molding or bead is formed on the edge or margin 50 of the board without appreciably marring the

embossing in the raised and molded part, and then applying a coating of a non-vitreous composition or varnish to the bright metallic upper surface of the board, which imparts to said board the color and luster of brass. I thus produce from the cheaper grades of heavy tin a stiff and durable board, which has the beauty and finish of the more expensive and less durable brass boards. 55

The non-vitreous composition which I apply to my board is when dry very hard, glossy, tough, and refractory, and its composition is substantially as follows: To two parts, by measure, of linseed-oil and one part, by measure, 65 of spirits of turpentine I add enough gum-copal or gum-dammar to give the proper consistency, and then add, as a coloring-matter, dragon's-blood and gamboge in quantity sufficient to impart the proper tint and color of 70 brass. Dragon's-blood imparts a more or less coppery tint. This coating must be allowed to dry thoroughly, and artificial heat may be employed for the purpose. 75

Any composition that possesses the above qualities may be employed to coat the board; but that above described will produce good results. I may apply this composition before the plate is embossed, or after the board is molded or beaded. I prefer to apply it after 80 the beading.

In the drawings, which serve to illustrate my invention, Figure 1 is a face view of a stove-board constructed according to my invention. Fig. 2 is a diametrical transverse 85 section of the same on line 22 in Fig. 1. Fig. 3 is a fragmentary sectional view on a large scale, designed to show the transparent non-vitreous coating on the board.

a represents the molding on the margin of the board, over which, it will be seen, the embossed pattern extends in a continuous manner. 90

b in Fig. 3 represents the coating on the face of the board, which gives the latter the 95 appearance of brass.

Having thus described my invention, I claim—

1. The herein-described method of making a stove-board from a single sheet of refractory 100 tin-plate, which consists in first embossing the entire surface of a tin-plate of sufficient size to

make the board, then cutting said plate to the proper size and shape for the board, and then forming on its edge or margin a molding or raised bead without effacing the embossing on the part forming said molding or bead.

2. The herein-described method of making a stove-board from a single sheet of refractory tin-plate, which consists in first embossing the entire surface of a tin-plate of sufficient size to make the board, then cutting said plate to the proper size and shape for the board, then forming on its edge or margin a molding or raised bead without effacing the embossing on the part forming said molding or bead, and, lastly, applying to the face of said board a non-vitreous coating, as described, to impart to the board the color and luster of brass.

3. As an improved article of manufacture, a stove-board constructed of a single sheet of embossed tin-plate with a molded edge, the embossed pattern of the plate extending con-

tinuously over the entire surface of said board and over the raised mold or bead on its edge, substantially as set forth.

4. As an improved article of manufacture, a stove-board constructed of a single sheet of embossed tin-plate with a molded edge, the embossed pattern of the plate extending continuously over the entire surface of said board and over the raised mold or bead on its margin, and the face of said board covered with a transparent non-vitreous varnish, as described, whereby the color and luster of brass are imparted to the board, substantially as set forth.

In witness whereof I have hereunto signed my name in the presence of two subscribing witnesses.

A. IRVING GRIGGS.
